19 Claims. (Cl. 164—112)

This invention relates to machines for making records on statistical cards.

In making records on statistical cards, as for example, by punching holes therein, systems have been employed according to which a card of standard size is virtually divided into two halves longitudinally, the upper and lower halves of the card each having an equal number of half columns for the reception of records. This arrangement doubles the capacity of a standard card but requires that some form of coding be employed when making the records, for example a code according to which a single hole in one position in a half column represents one digit, while a hole in the same position together with a second hole in another position in the same half column represents a different digit.

The present invention has for its main object to provide an improved form of mechanism for actuating the record-forming elements in a machine for making coded records in either or both halves of each column of a record card which is virtually divided into two halves longitudinally as described above.

A further object of the invention is to provide a machine which can be used to make coded records in either the upper or lower half of a card, or to make single records each in a full column of a card.

According to the present invention a machine for making records on statistical cards comprises in combination a column of record-forming elements whereof the elements in one half of the column of elements represent the same data as corresponding elements in the other half of the column, and in an embodiment of the invention now favored such machine comprises a plurality of crossbars each disposed with its ends resting on the upper ends respectively of two corresponding record-forming elements in the column, a pivoted actuator for each crossbar, each of said actuators resting on its associated crossbar between the ends of the latter, and means for blocking downward movement of either end of each crossbar at will, whereby on depression of any actuator, the blocked end of the associated crossbar serves as a fulcrum about which said crossbar rocks to operate the record-forming element on which its other end rests, the other record-forming element remaining inoperative.

The record-forming elements may be in the form of punches for perforating record holes in the cards, and in this connection a presently preferred embodiment of the invention is a machine comprising in combination a column of punches

whereof each punch in one half of the column has the same value as the correspondingly positioned punch in the other half of the column, a plurality of double-armed levers each having one end resting on the upper end of a punch in one half of the column and its other end resting on the upper end of the corresponding punch in the other half of the column, a pivoted actuator for each of said levers, each of said actuators resting on the associated lever midway between the ends of the latter, and means for locking the punches in either half of the column against downward movement at will, whereby on depression of any actuator the locked punch on which one end of the associated lever rests serves as a fulcrum about which the associated lever rocks to operate the unlocked punch on which its other end rests.

According to a further feature of the invention each of the record-forming elements in the column may be provided with an additional pivoted actuator individual thereto and overlying a projection or shoulder on the associated record-forming elements, and the machine may include means for disabling the blocking means for all the record-forming elements simultaneously, whereby the same machine can be used for recording data by single records (e. g., perforations) each in a full column of (e. g., twelve) index point positions, or by one, or two, records (e. g., perforations) duplicated in the lower and upper halves of a column of (e. g., six) index point positions, or by records of the latter kind in either half column.

In order that the invention may be more fully understood one embodiment thereof will now be described by way of example with reference to the accompanying diagrammatic drawings which illustrate the invention applied to a machine for

forming records by punching holes in statistical cards.

In the drawings:

Fig. 1 is a side elevation of the machine, partially in section, with the base broken away at its ends, and with certain parts omitted, to wit, the actuating bar 20a and the arm 155 shown in Figs. 2 and 7 and the left-hand end portion of the lever 38a, this lever best shown in Fig. 12.

Fig. 2 is a plan, partly in section on the line 50 II—II in Fig. 1.

Fig. 3 is an end elevation of the machine, partly in section,

Fig. 4 is a part section on the line IV—IV in Fig. 1, illustrating part of the means for guiding the punches which form the records,

Fig. 5 is an exploded view of the punch guide means shown in Fig. 4.

Fig. 6 is a part horizontal section on the line VI—VI in Fig. 1.

Fig. 7 is a perspective view of the punch selecting and actuating mechanism, including the crossbars,

Fig. 8 is a horizontal section on the line VIII—VIII in Fig. 1, certain actuating levers for the punches being omitted.

Fig. 9 is a perspective view from the back of the machine showing an interlocking mechanism for certain setting slides which serve to control the punch locking means,

Fig. 10 is a fragmentary plan view of a record card perforated in the upper halves of its columns according to a code which conveniently may be used,

Fig. 11 is a view looking down on the two banks of keys provided, with the keyboard plate removed, and showing in dot-and-dash lines the key bank to the left in Fig. 2, and in full lines the key bank to the right in Fig. 2 and the punch-actuating levers operated by the keys of that bank, the several punch carriers being outlined in top plan in full lines, and the locations of the crossbar midpoints laterally of the machine being indicated by dot-and-dash arrows,

Fig. 12 is a view similar to Fig. 11, but showing the punch-actuating levers operated by the keys of the bank to the left in Fig. 2, the levers illustrated in Fig. 11 being only partially shown to avoid confusion as between the levers of Figs. 11 and 12; it being also pointed out that in Fig. 12 the dot-and-dash arrows correspond to those of Fig. 11 and the two punch carriers indicated are the top and bottom punch carriers as seen in Fig. 11,

Fig. 13 is a detail view, showing in top plan a horizontal locking plate, together with certain associated devices, and

Fig. 14 illustrates a modification of the means for blocking the punches allotted to either half column of a record card and for then rendering operative the punches allotted to the other half column.

In the drawings like references indicate the same or similar parts.

In the embodiment illustrated in the drawings the machine comprises a bedplate 1 carrying supports 2 across which is secured, by screws 3, a lower bridge plate 4. Below the bridge plate 4 the bedplate 1 carries a die plate 5 having twelve holes 5a therein, and above the die plate a stripper plate 6 formed with twelve corresponding holes.

The lower bridge plate 4 is formed with a longitudinal opening 7 (Fig. 5) through which pass the punch carriers. These last are twelve plates 8 each having a punch 9 depending from its lower end. Plates 8 are guided at their upper ends by a comb plate 10 secured to the lower bridge plate 4 by screws 11 and a retaining bar 12 secured to the plate 4 by screws 13. At their lower ends the plates 8 are guided by the passage of the punches 9 through the respective holes in the stripper plate 6. A spring 14 is disposed around each punch 9 between the stripper plate 6 and the lower edge of the corresponding plate 8, said springs urging the punch upwardly, and the upward movement being limited by engagement of a shoulder 8a (Fig. 7) on the plate 8 with the underside of plate 4.

The machine thus includes twelve punches arranged in a column in accordance with the twelve

index point positions in a column of a record card. Each card has 45 columns, each having twelve index point positions, but the card is divided by an imaginary line lengthwise into two halves, there being six index point positions in each half column.

The punches 9 are controlled by a keyboard as will be explained later and the machine also includes a card carriage 15 having an escapement mechanism controlled by the keys for traversing the card column by column under the punches 9. The carriage 15 and its escapement mechanism are similar to that described in British patent specification No. 430,251.

15 The machine as described herein is intended for use in punching sterling monetary amounts and the six index point positions in each half column are used to represent the even digits or values, 0, 2, 4, 6, 8, and the odd digit 9, while the other odd digits are respectively represented by the next higher even value position and the 9 position, the digit 11 being represented by the 0 and 9 combination.

20 In other words, as shown in Fig. 10, each even number—0, 2, 4, 6, 8—is recorded by punching a single hole in the card, the odd number 9 is similarly recorded, and the other odd numbers—1, 3, 5, 7 and 11—are each recorded by punching two holes one of which is always the same punching as for the 0 hole. The number or value 1 is represented by the 0 and 2 combination, the number 3 by the 0 and 4 combination, the number 5 by the 0 and 6 combination, the number 7 by the 0 and 8 combination, and the number 11 by the 0 and 9 combination.

25 This system of coding differs somewhat from that described in British patent specification 434,499 disclosing certain features which, or adaptations of which, are incorporated in the machine herein illustrated. Such features will be later specified.

30 Since in the machine herein illustrated the 0 and 9 combination is used for recording the number 11, it is desirable to have the punches for recording the 0 and 9 values alongside each other. Hence the machine herein illustrated includes six punches with values so assigned thereto that the punches for the values 2, 4, 6, 8, 0 and 9 are arranged in that order relative to the index point positions of a half column of the record card as these positions are successively located one below another along the column. Starting with the punch at the extreme left in Figs. 3 and 7, this punch, which in these two views is additionally marked A, is the 2-value punch and the next five punches to the right, which in regular sequence are additionally marked B, C, D, E and F (see also Fig. 11), are respectively for recording the values 4, 6, 8, 0, and 9. The six punches shown in Figs. 3 and 7 beyond the punch F are in these views additionally marked A', B', C', D', E', and F'; the punch A' for recording the same value as the punch A, the punch B' for recording the same value as the punch B, and so on.

35 It will be seen that in order to punch holes in the various index point positions only six punches are required for each half column, so that the column of twelve punches may be regarded as being divided into two half columns of six punches each, and each punch in one half column as having a punch of corresponding value in the other half column.

40 Six punch actuating bars 20 are provided of which five are respectively appropriated to the

even digits 2, 4, 6, 8, 0, while the sixth (indicated at 20a) is appropriated to the digit 9.

Each of the five actuating bars 20 and the actuating bar 20a rests freely on a pivot pin 21 engaging in a socket 22 formed in the underside of the bar, said pin 21 projecting vertically from a holder 32 pivotally mounted at the centre of a corresponding crossbar or double armed lever 23. Each crossbar 23 has one end 24 resting on the upper end of a plate 8 in one half column and its other end 25 resting on the upper end of the corresponding plate 8 in the other half column.

Considering for example the plate 8 carrying the 2-value punch in the left hand half column in Fig. 3, which is the punch additionally marked A in this view, and the corresponding plate 8 carrying the 2-value punch in the right hand half column, which is the punch additionally marked A' in this view, then a crossbar 23 common to these two plates will have its ends 24 and 25 resting respectively on the left hand plate and the right hand plate, the common crossbar 23 being operable by the one actuating bar 20. Such crossbar is the one shown to the left in Fig. 7.

The pin 21 through which a bar 20 or 20a transmits movement to a cross bar 23 is mounted as follows:

As can be seen from Fig. 6 the crossbars 23 are mounted side by side in contact and are held in position by two stepped plates 39 and 31 of which the steps engage the ends of the bars 23 to maintain them in correct position. Plate 39 is supported on short posts 16 to which it is attached by screws 17 and plate 31 is supported on short posts 18 to which it is attached by screws 19. Each pin 21 is carried by a holder 32 rounded at the bottom to fit a correspondingly rounded depression 33 formed in the upper edge of the crossbar 23 so that the bar 23 can rock about the centre of the lower end of the member 32.

It will be seen that four of the members 32 are held in position laterally by the adjacent crossbars 23 and in order to prevent the two outside members 32 at the right hand end and left hand end in Fig. 6 from falling out, a retaining plate 34 is screwed to the outside face of each of the two outside crossbars 23 of the group.

As can be seen from Fig. 7 the plates 8 are cut away at the top as indicated, for example at 8b in Fig. 7, to admit the downwardly projecting portion 23a of any crossbar which passes over them, this downwardly projecting portion being provided to strengthen the cross bar in view of the depression 33 formed in the upper edge of the bar 23 to receive the member 32.

The position of the pivot provided by the pin 21 and the socket 22 in each actuating bar 20 and in the actuating bar 20a is near the left hand end of the actuating bar in Fig. 1, and closely adjacent to its left hand end the actuating bar is freely pivoted about a fulcrum pin 35 screwed into an upper bridge plate 37. The fulcrum pin 35 is rounded at its lower end and enters a socket 36 in the upper edge of the bar.

Accordingly by depressing the right hand end of a bar 20 or 20a in Fig. 1 the bar rocks clockwise about the fulcrum pin 35 and through pivotal connection 21, 22 will move the associated cross bar 23 bodily downwards.

In order to effect this rocking of the cross bars 23 each of the five bars 20 (corresponding to the digits 2, 4, 6, 8 and 0, respectively) is provided with a key lever 38 (Figs. 2 and 12) loosely pivoted on a shaft 39 (Figs. 1 and 2) mounted in bearings

40 projecting upwardly from the upper bridge 37, each key lever 38 having a key stem 41 provided with a key 42 for operating it. Each key lever 38 also has a downward nose 43 (Figs. 1 and 7) formed on its under edge which bears on the upper edge of the actuating bar 20 therebelow near its right hand end so that depression of a key 42 rocks its key lever 38 down about the shaft 39 and thereby actuates said bar by rocking it down about the pivot 35, 36.

The key 42a bearing the numeral 9 is similarly connected to a key lever 38a freely mounted on the shaft 39 and carrying a pin 150 (Figs. 2 and 12) overlying the 9 actuating bar 20a. Thus depression of the No. 9 key will actuate the bar 20a, but rocking of the shaft 39 will not affect the No. 9 key.

Each of the five keys 42b bearing the numerals "1", "3", "5", "7", and "11" is similarly connected to a key lever 38b freely pivoted about the shaft 39 and carries a pin 151. Each of these pins overlies a step 152 in one of five collars 153 (Figs. 2 and 7) fixed to the shaft 39. Each key lever 38b also carries a pin 154 overlying the actuating bar

20 which is directly actuated by the key 42 bearing the next higher even number, i. e., the key lever 38b of the "1" key 42b carries a pin 154 overlying the bar 20 for operating the 2-value punch, and so on. The lever 38b of the "11" key 42b, however, carries a pin 154 overlying the bar 20 for operating the 0-value punch.

Secured to the shaft 39 is an arm 155 carrying a pin 156 overlying the bar 20a for operating the 9-value punch.

When any key 42b is depressed the pin 154 on its key lever 38b rocks the actuating bar 20 corresponding to the next higher even number and the pin 151 on said lever acts through the associated collar 153 to rock the shaft 39 and at the same time the arm 155 through the pin 156 rocks the actuating bar 20a. Thus depression, for example, of the "5" key will rock the actuating bar 20 for operating the 6-value punch and also the actuating bar 20a for operating the 9-value punch.

Each lever 38b carries a depending lug 38c and these lugs together with a similar lug 155c act as guides for the ends of the bars 20, 20a.

The mechanism as so far described is similar to that described in British patent specification No. 434,499, except for the crossbars 23 and an added tier or bank of punches.

The upper bridge plate 37 is supported (Figs. 1 and 3) by four posts 44, one at each corner, standing up from the supports 2.

From the foregoing it will be observed that with the construction thus far described actuation of any key 42 will through its lever 38 force down the actuating bar 20 underlying such lever and thereby cause depression of both ends 24 and 25 of the associated cross bar 23 simultaneously, with the result that the two plates 8 engaged by the two ends of said crossbar will both be depressed so that the apparatus would tend to punch a hole in one half column of the card and also a hole of the same value in the other half of the same column. A similar result is obtained by actuation of the "9" key 42a as then the pin 150 on the lever 38a, which pin overlies the actuating bar 20a, forces this bar down thereby to depress both ends of the cross-bar engaged by the bar 20a.

Also, when any of the keys 42b is actuated, these for punching a two-hole record, the appropriate one of the actuating bars 20, and with it the actuating bar 20a, will both be rocked down, and each of these two downrocked bars will act on the

associated two cross bars simultaneously; and the consequent depression of both ends of these cross-bars will operate the four plates 8 engaged by said ends, so that the apparatus would tend to punch a two hole record in one half column of the card and also a two-hole record of the same value in the other half of the same column.

In order to lock the punches in either half of the column two locking slides 50 and 51 (Figs. 7 and 8) are provided, one on each side of the column of punches 9. The slides 50 and 51 are guided in slots formed in a bracket 52 secured to the inside face of the left hand support 2 and at their right hand ends (Figs. 3 and 8) in slots formed in a plate 53 secured to the inside face of the right hand support 2. The right hand end of each slide passes through an opening 54 (Fig. 3) in the support 2 and is cut away underneath to leave an overhanging lug 55, the lug 55 of the slide 50 carrying a pin 56 and the lug 55 of the slide 51 carrying a pin 56a, for actuating the slide in the manner described below. Each slide also carries a pin 57 guiding a spring 58 and passing through a plate 59 screwed to the outside of the right hand support 2 which is cut away at 60, Fig. 8, for the purpose described below. The springs 58 are compressed between the end of the slide and the inside of the plate 59.

The slide 50 has six teeth 61 on its upper edge for co-operation with the plates 8 carrying the six punches 9 in the left hand half of the column (Fig. 3) and the slide 51 has six teeth 62 for co-operation with the six plates 8 carrying the punches in the right hand half of the column, see Fig. 7.

The spacing of the teeth 61 on slide 50 and of the teeth 62 on slide 51 is the same as the pitch of the punches 9 and by displacing the slides longitudinally each slide can occupy a left hand, or effective position, or a right hand, or ineffective position.

The slides are provided with an interlock as hereinbelow described, by means of which when one slide is set in the effective position the other slide is set in the ineffective position and vice versa, and if for example the slide 50 is moved to the right hand end of its travel (Figs. 3 and 7) to position its teeth between the punches 9 of the left hand half column, at the same time the slide 51 is moved to the left to position its teeth 62 below the plates 8 carrying the punches 9 in the right hand half column to lock these punches against downward movement, leaving the punches in the other half of the column free to be operated so that each of the locked punches serves as a fulcrum about which the corresponding crossbar 23 rocks to depress the corresponding punch in the other half of the column.

With the slides 50 and 51 in the positions shown in the drawings, if for example the "2" key 42 is depressed this key will cause the actuator bar 20 at the extreme left in Figs. 3 and 7 to rock clockwise thereby moving the corresponding crossbar 23 downwardly. Since the right hand end 25 of this bar is resting on the "2" plate 8 in the right hand half column which carries the punch 9 additionally marked A' and since this plate is locked against downward movement by the corresponding tooth 62 of the slide 51, this plate 8 will serve as a fulcrum for the right hand end 25 of bar 23 which will consequently rock counterclockwise about this end, and its left hand end 24 will depress the plate 8 in the left hand half column which carries the punch 9 additionally marked A, thereby perforat-

ing a card with a hole in the 2 value position in the left hand half column.

Conversely if the slide 50 is moved to the left thereby locking the plates 8 in the left hand half column and the slide 51 is at the same time shifted to the right depression of the "2" key 42 key will cause the corresponding crossbar 23 to rock clockwise about the plate 8 in the left hand half column thereby depressing the corresponding plate in the right hand half column to punch a hole in the 2-value position in that half column of the card.

In order to control the slides 50 and 51 the following mechanism is provided:

Pivoted about a pin 64 extending across the opening 60 (Fig. 8) in the support 2 are two levers 66 and 67 (Figs. 2, 3, and 7), the lower end of lever 66 abutting against the pin 56 of slide 50, while the lower end of lever 67 abuts against the pin 56a on the right hand end of slide 51. The upper ends of the levers 66 and 67 project into a slot marked 68 in Fig. 2 cut in the right hand end of the upper bridge plate 37 and engaging the upper end of lever 66 is a lug 69 bent down from a setting slide 70 while the upper end of lever 67 is engaged by a corresponding lug 71 bent down from a setting slide 72. At their right hand ends in Fig. 3, the slides 70 and 72 are guided by a bracket 73 (Figs. 1 and 2) screwed to a top plate 74 secured to the upper bridge plate 37 by screws 75 and at their left hand ends the slides are guided (Fig. 9) in slots formed in lugs 76, 76 bent up from the top plate 74.

The setting slide 70 is controlled by a key 80 (Figs. 1, 2 and 9) attached to a key stem 81 passing through a slot 82 in a plate 83 supported by four posts 84 extending upwardly from the upper bridge plate 37. The lower end of the key stem 81 (Fig. 9) is cut away to form a cam face 85, the reduced end 86 of the stem passing through a slot 87 in the plate 74, this slot also extending through the plate 37 beneath. As the slot 87 must be the full width of the key stem 81 to allow for depression of the latter a guide 88 is provided which bears against the rear face of the key stem. This guide 88 is constituted by a lug bent off from a strip 89 secured at 90 to a post 91 upstanding from the plate 74.

In order to control the setting slide 72 a key 92 having a key stem 93 is provided, the key stem 93 being cut away at its lower end to form a cam face 94 and being guided in the same manner as key stem 81.

The key stems 81 and 93 are urged upwardly by means of springs 81a and 93a respectively, the last-mentioned spring not being seen in Fig. 9 but being shown in Fig. 1.

On depression of, for example, the key 80 the cam face 85, acting on a shoulder 95 of the setting slide 70 pushes said slide rearwardly (to the left side in Fig. 3) into its ineffective position against the action of a spring 96, the slide remaining locked in this position by a latch 97 pivoted at 98 to the post 91 and acted upon by a spring 99. In Fig. 9 the latch 97 is shown spaced away from the post 91 for the sake of clarity, whereas in fact the latch is close up against the post as can be seen from Fig. 1.

When the control slide 70 moves in the above described manner the lug 69 rocks the lever 66 counter-clockwise about the pivot 64 and the lower end of said lever acting on the pin 56 pulls the slide 50 to the right into the position shown in Fig. 7 against the action of spring 58, thereby bringing the teeth 61 between the plates 8 in the

upper half column so that the punches in the upper half column are free to operate.

If it is now desired to punch holes in the lower half column of a card the key 92 is depressed and the cam face 94 acting on a shoulder 100 of the setting slide 72 pushes said slide rearwardly into its ineffective position against the action of a spring 101, the slide remaining locked in this position by a latch 102 pivoted at 103 to the post 91, and acted upon by a spring 104.

When the control slide 72 moves thus the lug 71 rocks the lever 67 counter-clockwise about the pivot 64 and the lower end of said lever acting on the pin 56a pulls the slide 51 to the right in Fig. 7 thereby bringing the teeth 62 in between the plates 8 in the lower half column so that the punches in this half column are now free to be operated.

In order to disable the punches in the upper half column when the key 92 is depressed the key stem 93 carries an arm 105 having a depending lug 106 disposed above the tail of the latch 97 for the slide 70 so that when key 92 is depressed the lug 106 rocks latch 97 to release the slide 70 which is moved to the right in Fig. 7 by its spring 96 (Fig. 9) thereby moving lug 69 away from the upper end of lever 66. Spring 58 (Figs. 3 and 7) then pushes slide 50 to the left thereby bringing its teeth 61 under the plates 8 in the upper half column so that these plates serve as abutments about which the levers 23 rock to actuate the punches 9 in the lower half column.

Similarly the key stem 81 carries an arm 107 having a lug 108 depending above the tail of the latch 102 for the slide 72 so that on depression of the key 80 the lug rocks the latch 102 to release the slide 72 thereby permitting the spring 58a to push the slide 51 to the left and thus bring the teeth 62 under the plates 8 of the lower half column so that these plates serve as abutments about which the cross bars 23 rock to actuate the punches 9 in the upper half column.

In order to enable one and the same machine to be used for punching data either in a full column or in a lower or upper half column at will, each of the twelve punches 9 in the full column may be provided with an independent actuating lever 110 controlled from a corresponding one of a bank of twelve additional keys 111.

Each of the actuating levers 110 (Figs. 1, 2, 11 and 12) is connected to the stem 112 of its key 111 by a loop 113 formed at the end of the lever 110 and embracing a reduced portion 114 of the key stem. See in this connection the key stem 112 at the right in Fig. 1, and the "1" key 111 in Fig. 11.

As illustrated in Fig. 1 and in the case of the "2" key 42 in Fig. 12, the just described manner of coupling the key stems 112 with the levers 110 is employed also for operatively connecting the key stems 41 of the keys 42 with the levers 38, the key stem of the key 42a with the lever 38a, and the key stems of the keys 42b with the levers 38b. Each lever 110 at its forward end has a depression 115 in its upper edge which is maintained in engagement with a pivot pin 116 by a bracket 117 screwed to a plate 118 depending from the edge of the lower bridge plate 4.

Each key lever 110 overlies a pin 119 (Figs. 3, 9 and 11) projecting from the side of the plate 8 carrying the associated punch so that, assuming the punches to be free to move, depression of any of the additional keys 111 will cause operation of the corresponding punch 9.

In order thus to free the punches and so condition the machine for punching data in a full column a third control key 120 for the slides 70 and 72 is provided as shown best in Fig. 9. The stem 121 of this key is guided in a manner similar to that described for the key stem 81 and the lower end of this key stem 121 is cut away to form a cam face 122 wide enough to overlap shoulders 123 and 124 on both slides 70 and 72 simultaneously.

With the parts in the positions shown in Fig. 7 the slide 70 is in its rearward position so that the slide 50 controlled thereby is in its ineffective position to the right and the punches in the upper half column are free to operate, the punches in the lower half column being locked by the teeth 62 of slide 52 which has been permitted to move to the left by slide 72 which has been moved to the right by its spring 101.

On depression of key 120 the cam face 122, acting on shoulder 124, pushes slide 72 also rearwardly in which position it is held by latch 102. By this means slide 51 will have been moved to the right thereby releasing the punches in the lower half column so that all the punches in the complete column are now free to be operated by the additional bank of keys 111.

If it is desired for example to revert to punching in the upper half column only, then key 80 will be depressed whereby the lug 108 will release the latch 102 for the slide 72 thereby permitting slide 51 to move to the left and bring its teeth 62 under the plates 8 in the lower half column and so locking them, leaving the other slides 70 and 50 in the position shown in Fig. 7 so that the punches in the upper half column are free to be operated.

It is desirable as a safeguard to lock the keys 111 of the additional bank when the machine is set for punching in either the lower or the upper half column of a card, and to this end each slide 70 and 72 carries an upstanding pin 125, 126 (Figs. 2, 3 and 7) co-operating with a lever 127 (Figs. 1, 2, and 13) pivoted at 128 to the underside of the keyboard plate 129. Mounted in grooves formed between the underside of plate 129 and the underhanging flanges 130 of bars 131 is a locking plate 132 for the key stems 112, this plate having slots 133, marginal cut-outs 133' and other marginal shapings as shown in Fig. 13, each for providing an edge portion engageable in a notch formed in an adjacent stem; one of such notches being marked 112a in Fig. 13. On an extension 135 of the plate 132 is a pin 136 against which abuts the end 137 of lever 127.

When either key 80 or 92 is depressed the respective pin 125 or 126 rocks the lever 127 counter-clockwise about its pivot 128 and the end 137 of the lever pulls the locking plate 132 into a position in which its slots 133 engage the notches of the key stems 112 thereby locking them against operation.

When both slides 70 and 72 are in their rearward position owing to depression of key 120 the lever 127 is free and a retractile spring 139 pulls the locking plate 132 into a position in which its slots 133 are disengaged from the notches in the key stems 112. The spring 139 as shown most clearly in Fig. 13 is connected at its opposite ends to the locking plate 132 and to an arm 140 forming part of a suitable bracket (not shown) secured to the underside of keyboard plate 129 beyond the field of movement of the locking plate.

In order to operate the escapement mechanism 75 a bail plate 160 (Figs. 1 and 8) extends below

the punch carrying plates 8 and carries brackets 161 by means of which it is pivoted on pins 162. Freely mounted on a shaft 163 is a bail 164 carrying near its centre a lug 165 which is engaged by a tail 166 projecting from a small adjustable plate 166a (Fig. 8) having two slots 166b for screw securing to the bail plate 160. When any of the plates 8 is depressed its lower right hand corner in Fig. 1 rocks plate 160 counter-clockwise about its pivots 162 and the tail 166 rocks bail 164.

The bail 164 corresponds to the horizontal part of the angle plate 17 described in British patent specification No. 430,251, and carries a pin 167 bearing on an arm 168 by means of which the escapement pawl 169 is operated. The parts 167, 168, and 169 correspond to the parts 29c, 29 and 24 described in the British specification No. 430,251 above referred to.

Instead of employing the two locking slides 50 and 51 described above, the teeth 61 of the slide 50 and the teeth 62 of the slide 51, may be disposed on a single locking slide disposed along one side of the column of punches 9. Such a construction is illustrated in Fig. 14, where a single slide 175 is shown as longitudinally shiftable on fixed parts 176, 176 of the machine and as carrying along its top a group of teeth 177, corresponding to the teeth 61, and also a group of teeth 178, corresponding to the teeth 62. The group of teeth 178 are displaced along the slide, from the group of teeth 177, by a distance equal to half the pitch of the punches 9, so that, when the slide is at one end of its travel, the teeth 177 will be disposed below the plates 8 in the one half column while the teeth 178 are in between the plates 8 of the other half column, whereas when the slide is moved to the other end of its travel the teeth 177 will be between the plates 8 in the one half column, and the teeth 178 will be below the plates 8 in the other half column. The plates 8 and punches 9 are indicated in Fig. 14 in dot-and-dash lines.

Accordingly, by shifting this single slide lengthwise, the teeth 177 or the teeth 178 can be brought into register with the plates 8 in the corresponding half of the column to lock them against movement, leaving the punches in the other half of the column free to be operated, each of the locked punches serving as a fulcrum about which the corresponding crossbar rocks to depress the corresponding punch in the other half column in the manner already described above.

The single locking slide may be biased to one of its extreme positions by means of a spring 180, and a key 181 may be provided to displace it to the other position, a latch device 182, releasable on actuation of another key 183, being provided to retain the slide in the position to which it has been set by the first mentioned key. The keys 181 and 183 are shown as provided with conventional return springs 184 and 185 respectively. Normally the slide 175, connected as at 186 to one end of the spring 180, and with the other end of this spring connected to a fixed part of the machine as at 187, would be positioned as shown against a stop 188. On depression of the key 181, the lower end of its stem would act cammingly relative to an inclined edge portion 189 on the slide, to shift the latter a sufficient distance to the left to dispose the teeth 178 below the plates 8 carrying the six punches at one end of the column of punches 9 and to place the teeth 177 between the plates 8 carrying the other six punches. The

latch 182, which includes a tooth 190 on the slide and a dog 191 fixedly pivoted at 192, would lock the slide as thus shifted, following clockwise rocking of the dog by the tooth 190 during movement of said tooth to the left; at the conclusion of which movement the spring 185 would cause the dog to drop behind the tooth 190. With the parts so arranged, the slide 175 would be returned to the position shown on depression of the key 183, which would rock the dog counterclockwise and break the latch 182 to free the spring 180 for return of the slide.

Constructions according to the invention in which means is provided for unlocking all twelve punches in the column simultaneously or for locking the six punches in either half column at will have the advantage that a single machine can be used for punching standard (e. g., 45 column) cards or for punching data in the upper half of a standard card which is divided into two parts lengthwise, or for punching data in the lower half of such a card.

Although the invention has been particularly described with reference to 45 column cards having twelve index point positions in each column it will be understood that it is also applicable to cards having a greater or smaller number of full columns and with any even number of index point positions in each full column or in that part of each full column on which the mechanism according to the invention is intended to operate.

Further although the formation of records by punching has been particularly described by way of example, the record forming elements may be arranged to impress the records on the cards in other ways, e. g., by printing spots, or making electro-conductive marks on the cards.

What I claim is:

1. In a machine for making statistical records the combination of a column of record-forming elements whereof the elements in one half of the column represent the same data as corresponding elements in the other half of the column a plurality of crossbars each disposed with its ends resting on the upper ends respectively of two corresponding record-forming elements in the column, an actuator to each crossbar, each of said actuators resting on its associated crossbar between the ends of the latter, and means for blocking downward movement of either end of each crossbar at will, whereby on depression of any actuator, the blocked end of the associated crossbar serves as a fulcrum about which said crossbar rocks to operate the record-forming element on which its other end rests, the other record-forming element remaining inoperative.

2. In a machine for perforating record holes in statistical record material, the combination of a column of punches, whereof each punch in one half of the column has the same value as the correspondingly positioned punch in the other half of said column, a plurality of crossbars, each having one end resting on the upper end of a punch in one half of the column and its other end resting on the upper end of the corresponding punch in the other half of the column, an actuator to each of said crossbars, each of said actuators resting on its associated crossbar midway between the ends of the latter, and means for locking all the punches in either half of the column against downward movement at will, whereby on depression of any actuator, the locked punch on which one end of a crossbar rests blocks said end of said crossbar against downward movement and thereby serves as a fulcrum about which said crossbar

rocks to operate the unlocked punch on which its other end rests.

3. In a machine for making statistical records the combination of a column of record-forming elements whereof the elements in one half of the column represent the same data as the corresponding elements in the other half of said column, a plurality of crossbars each disposed with its ends resting on the upper ends respectively of two corresponding record-forming elements in the column, an actuator to each crossbar, each of said actuators resting on its associated crossbar between the ends of the latter, means for blocking downward movement of either end of each crossbar at will, an additional actuator to each of said record-forming elements, and means for disabling the blocking means for all the crossbars simultaneously whereby the same machine can be used for recording data by single records each in a full column of index point positions, or by combination records in either a lower or an upper half column.

4. In a machine for perforating record holes in statistical record material, the combination of a column of punches whereof each punch in one half of the column has the same value as the correspondingly positioned punch in the other half of said column, a plurality of crossbars, each having one end resting on the upper end of a punch in one half of the column and its other end resting on the upper end of the corresponding punch in the other half of the column, an actuator to each of said crossbars, each of said actuators resting on its associated crossbar midway between the ends of the latter, and means for locking all the punches in either half of the column against downward movement at will, whereby on depression of any actuator, the locked punch on which one end of a crossbar rests blocks said end of said crossbar against downward movement and thereby serves as a fulcrum about which said crossbar rocks to operate the unlocked punch on which its other end rests, an independent actuator to each punch, and means for disabling the locking means for the punches in both halves of the column simultaneously, whereby the same machine can be used for recording data by single records each in a full column, or by combination records either in a lower or in an upper half column.

5. In a machine for making statistical records the combination of a column of record-forming elements whereof the elements in one half of the column represent the same data as corresponding elements in the other half of the column, a plurality of crossbars each disposed with its ends resting on its associated crossbar between the ends of the latter, an abutment on each record-forming element, two groups of locking abutments, and means for moving the locking abutments of one group under the abutments of the record-forming elements in one half of the column while moving the locking abutments of the other group clear of the abutments of the record-forming elements in the other half of the column and vice versa.

6. In a machine for perforating record holes in statistical record material, the combination of a column of punches whereof each punch in one half of the column has the same value as the correspondingly positioned punch in the other half of said column, a plurality of crossbars, each having one end resting on the upper end of a punch in one half of the column and its other end resting on the upper end of the corresponding punch

in the other half of the column, an actuator to each of said crossbars, each of said actuators resting on its associated crossbar midway between the ends of the latter, an abutment on each punch, two groups of locking abutments, and means for moving the locking abutments in one group under the abutments of the punches in one half of the column while moving the locking abutments of the other group clear of the abutments of the punches in the other half of the column and vice versa.

7. In a machine for perforating record holes in statistical record material the combination of a column of punches whereof each punch in one half of the column has the same value as the correspondingly positioned punch in the other half of said column, a plurality of crossbars, each having one end resting on the upper end of a punch in one half of the column and its other end resting on the upper end of the corresponding punch in the other half of said column, an actuator to each of said crossbars, each of said actuators resting on its associated crossbar midway between the ends of the latter, an abutment on each punch, two groups of locking abutments, means for moving the locking abutments of one group under the abutments of the punches in one half column while moving the abutments of the other group clear of the abutments of the punches in the other half column and vice versa, an independent actuator to each of said punches, and means for disabling both groups of locking abutments simultaneously.

8. In a machine for making statistical records the combination of a column of record-forming elements whereof the elements in half of the column represent the same data as corresponding elements in the other half of the column, a plurality of crossbars each disposed with its end resting on the upper ends respectively of two corresponding record-forming elements in the column, an actuator to each crossbar, each of said actuators resting on its associated crossbar between the ends of the latter, a locking slide for the record-forming elements in one half of the column, a locking slide for the record-forming elements in the other half of the column, an abutment on each of said record-forming elements, the abutments in each half column being disposed over the respective locking slide, teeth on each locking slide spaced apart along said slide by amounts equal to the spacing of the abutments in the respective half column, and means for moving one locking slide to bring its teeth into register with the abutments in the respective half column and the other locking slide to bring its teeth out of register with the corresponding abutments and vice versa.

9. In a machine for making statistical records the combination of a column of record-forming elements whereof the elements in one half of the column represent the same data as corresponding elements in the other half of the column, a plurality of crossbars each disposed with its ends resting on the upper ends respectively of two corresponding record-forming elements in the column, an actuator to each crossbar each of said actuators resting on its associated crossbar between the ends of the latter, a locking slide for the record-forming elements in one half of the column, a locking slide for the record-forming elements in the other half of the column, an abutment on each of said record-forming elements, the abutments in each half column being disposed over the respective locking slide, teeth

on each locking slide spaced apart along said slide by amounts equal to the spacing of the abutments in the respective half column, means for moving one locking slide to bring its teeth into register with the abutments in the respective half column and the other locking slide to bring its teeth out of register with the corresponding abutments and vice versa, an additional actuator to each of said record-forming elements and means for positioning both locking slides with their teeth out of register with the respective abutments.

10. In a machine for perforating record holes in statistical record material, the combination of a column of punches whereof each punch in one half of the column has the same value as the correspondingly positioned punch in the other half of the column, a plurality of crossbars, each having one end resting on the upper end of a punch in one half of the column and its other end resting on the upper end of the corresponding punch in the other half of the column, an actuator to each of said crossbars, each of said actuators resting on its associated crossbar midway between the ends of the latter, a locking slide for the punches in one half of the column, a locking slide for the punches in the other half of the column, an abutment on each punch, the abutments in each half column being disposed over the respective locking slide, teeth on each locking slide spaced apart along said slide by amounts equal to the spacing of the abutments in the respective half column, and means for moving one locking slide to bring its teeth into register with the abutments in the respective half column and the other locking slide to bring its teeth out of register with the abutments in the other half column and vice versa.

11. In a machine for perforating record holes in statistical record material, the combination of a column of punches whereof each punch in one half of the column has the same value as the correspondingly positioned punch in the other half of the column, a plurality of crossbars, each having one end resting on the upper end of a punch in one half of the column and its other end resting on the upper end of the corresponding punch in the other half of the column, an actuator to each of said crossbars, each of said actuators resting on its associated crossbar midway between the ends of the latter, a locking slide for the punches in one half of the column, a locking slide for the punches in the other half of the column, an abutment on each punch, the abutments in each half column being disposed over the respective locking slide, teeth on each locking slide spaced apart along said slide by amounts equal to the spacing of the punches in the respective half column, means for moving one locking slide to bring its teeth into register with the abutments in the respective half column and the other locking slide to bring its teeth out of register with the abutments in the other half column and vice versa, an independent actuator to each punch, and means for positioning both locking slides with their teeth out of register with the respective abutments.

12. In a machine for making statistical records the combination of a column of record-forming elements whereof the elements in one half of the column represent the same data as correspondingly positioned elements in the other half of the column, a plurality of crossbars each disposed with its ends resting on the upper ends respectively of two corresponding record-forming elements in the column, an actuator to each cross-

bar, each of said actuators resting on its associated crossbar midway between the ends of the latter, an abutment on each record-forming element, a locking slide to each half column, each of said locking slides having teeth disposed thereon for co-operation with the abutments on the record-forming elements in the respective half column, a spring to each locking slide each of said springs urging their respective slides into an effective position in which their teeth are disposed below the abutments of the record-forming elements in the respective half column, an actuating member individual to each locking slide for moving said locking slide to an ineffective position against the action of its spring, a latch for retaining each locking slide in the ineffective position when moved thereto, and releasing means for each latch, each of said releasing means being operable by the actuating member for the slide associated with the other of said latches.

13. In a machine for perforating record holes in statistical record material, the combination of a column of punches whereof each punch in one half of the column has the same value as the correspondingly positioned punch in the other half of the column, a plurality of crossbars, each having one end resting on the upper end of a punch in one half of the column and its other end resting on the upper end of the corresponding punch in the other half of the column, an actuator to each of said crossbars, each of said actuators resting on its associated crossbar midway between the ends of the latter, a locking slide for the punches in one half of the column, a locking slide for the punches in the other half of the column, an abutment on each punch, the abutments in each half column being disposed over the respective locking slide, teeth on each locking slide spaced apart along said slide by amounts equal to the spacing of the abutments in the respective half column, an actuating member individual to each locking slide for moving said locking slide to an ineffective position against the action of its spring, a latch for retaining each locking slide in the ineffective position when moved thereto, and releasing means for each latch, each of said releasing means being operable by the actuating member for the slide associated with the other of said latches.

50 14. In a machine for making statistical records the combination of a column of record-forming elements whereof the elements in one half of the column represent the same data as correspondingly positioned elements in the other half of the column, a plurality of crossbars each disposed with its ends resting on the upper ends respectively of two corresponding record-forming elements in the column, an actuator to each crossbar, each of said actuators resting on its associated crossbar midway between the ends of the latter, an abutment on each record-forming element, a locking slide to each half column, each of said locking slides having teeth disposed thereon for co-operation with the abutments on the record-forming elements in the respective half column, a spring to each locking slide, each of said springs urging their respective slides into an effective position in which their teeth are disposed below the abutments of the record-forming elements in the respective half column, an actuating member individual to each locking slide for moving said locking slide to an ineffective position against the action of its spring, a latch for retaining each locking slide in the ineffective position when moved thereto, releasing means for

55

60

each latch, each of said releasing means being operable by the actuating member for the slide associated with the other of said latches, an independent actuator to each record-forming element, and means for positioning both locking slides in the ineffective position.

15. In a machine for making statistical records the combination of a column of record-forming elements whereof the elements in one half of the column represent the same data as correspondingly positioned elements in the other half of the column, a plurality of crossbars each disposed with its ends resting on the upper ends respectively of two corresponding record-forming elements in the column, an actuator to each crossbar, each of said actuators resting on its associated crossbar midway between the ends of the latter, an abutment on each record-forming element, a locking slide to each half column, each of said locking slides having teeth disposed thereon for co-operation with the abutments on the record-forming elements in the respective half column, a spring to each locking slide, each of said springs urging their respective slides into an effective position in which their teeth are disposed below the abutments of the record-forming elements in the respective half column, a setting slide individual to each locking slide for moving said locking slide to an ineffective position against the action of its spring, an actuating member individual to each setting slide, each of said actuating members having a cam surface co-operating with an operative edge of the associated setting slide to actuate the latter, a third actuating member common to both setting slides, said third actuating member having a cam surface co-operating with the operative edges of both said setting slides, a latch for retaining each setting slide in the operated position and releasing means for each latch, each of said releasing means being operable by the actuating member individual to the setting slide associated with the other of said latches.

16. In a machine for making statistical records, the combination of a column of record-forming elements, key operated means for actuating all said elements and including a plurality of keys and a plurality of wholly mechanically acting operative connections between each of the keys and a different one of said elements, wholly mechanically acting devices each for actuating a different record-forming element in a part of the column and for simultaneously actuating a record-forming element having corresponding placement in another part of the column, a second key operated means including said devices and a second plurality of keys and wholly mechanically acting operative connections some of which are each between a different one of some of the last-named keys and a different one of said devices and others of which are each between a different one of others of the last-named keys and a different plurality of devices, and means for at will

disabling said devices relative to the record-forming elements of one or the other part of the column.

17. In a machine for making statistical records, the combination of a column of record-forming elements, key operated means for actuating all said elements and including a plurality of keys and a plurality of wholly mechanically acting operative connections between each of the keys and a different one of said elements, wholly mechanically acting devices each for actuating a different record-forming element in a part of the column and for simultaneously actuating a record-forming element having corresponding placement in another part of the column, a second key operated means including said devices and a second plurality of keys and wholly mechanically acting operative connections some of which are each between a different one of some of the last-named keys and a different one of said devices and others of which are each between a different one of others of the last-named keys and a different plurality of said devices, means for disabling said devices relative to the record-forming elements of one or another part of the column, and means for disabling said devices relative to all the record-forming elements of the column.

18. In a machine for making statistical records, the combination of a column of record-forming elements, key operated means for actuating all said elements and including a plurality of keys and a plurality of wholly mechanically acting operative connections between each of the keys and a different one of said elements, wholly mechanically acting devices each for actuating a different record-forming element in a part of the column and for simultaneously actuating a record-forming element having corresponding placement in another part of the column, a second key operated means including said devices and a second plurality of keys and wholly mechanically acting operative connections some of which are each between a different one of some of the last-named keys and a different one of said devices and others of which are each between a different one of others of the last-named keys and a different plurality of said devices, means for locking the first-named plurality of keys, means for disabling all of said devices, and means responsive to operation of the disabling means for releasing the locking means.

19. In a perforating machine, the combination of a column of punches, means operable to actuate any selected one of the punches, for straight punching, means for preventing operation of the first-named means, means operable to actuate any selected one or any selected plurality of the punches in a part of the column, for code punching, means operable at will for disabling the second-named means, and means responsive to operation of the disabling means for rendering the first-named means ineffective.

NORMAN GEOFFREY HOLDEN.
